UNITED STATES PATENT OFFICE.

HERMAN KERNGOOD, OF BALTIMORE, MARYLAND, ASSIGNOR TO THE
ALMA BUTTON COMPANY OF BALTIMORE CITY, A CORPORATION.

DETACHABLE BUTTON FOR GLOVES, &c.

No. 822,957.

Specification of Letters Patent.

Patented June 12, 1906.

Application filed March 8, 1905. Serial No. 248,982.

To all whom it may concern:

Be it known that I, HERMAN KERNGOOD, a citizen of the United States, residing at Baltimore city, State of Maryland, have invented new and useful Improvements in Detachable Buttons for Gloves, &c., of which the following is a specification.

My invention relates to an improvement in detachable buttons for gloves, plackets, and the like; and it consists, mainly, in a binding-ring adapted to inclose and form a support for the outer edge of the split flange of the socket of the female section of the button.

It further consists in certain novel features of construction and combinations of parts which will be hereinafter described and pointed out in the claim.

In the accompanying drawings, Figure 1 is a sectional view of this socket member of the female section, showing the binding-ring at the outer edge thereof. Fig. 2 is a view of this same part with the cap assembled. Fig. 3 is a view in perspective of the binding-ring. Fig. 4 is a view showing the parts assembled 25 and the male section in the socket, and Figs. 5 and 6 are views of the two parts of the male section or member of the button.

A represents the female and B the male section or member of the button, and the numeral 1 indicates the socket of the female section, it comprising the main cylindrical portion at the center and the restricted or reduced upper end 2, which is adapted to enter the orifice 3 in the cap 4 and be upset, as shown in Figs. 2 and 4, whereby the two parts—namely, the socket and cap—are assembled and permanently held together, as shown in Figs. 2 and 4. The lower end of the socket portion is bent outwardly in the form 40 of a circumferential flange 5, the outer edge of which is offset into a higher plane, as shown at 6. The lower half of this socket-section is split into two or more sections by means of the slits 7, which afford resiliency to the 45 mouth of the socket. A ring 8 is fitted to the outer edge of the flange 5, the lower flange of this ring 8 fitting beneath the offset portion 6 and lying approximately flush with the surface of the flange preferably, while the upper 50 turned flange of the ring is spun around the upper surface of the flange 5, thus forming a binding-ring therefor. This ring affords lateral support for the lower end of the socket-section, preventing its being spread beyond

its required and prescribed limitations, thus preventing this lower end from spreading unduly and taking a permanent set, which it would be liable to do without this binding-ring, the presence of which adds greatly to the efficiency, elasticity, resiliency, and durability of the button, the spring required for the admission of the male section being confined to the mouth of the socket, which mouth is formed by the roll 16 of the metal forming the member and which yielding or spreading is resisted at the outer edge of the flange 5 by reason of the support afforded by the binding-ring at that point.

The male section consists of the head 9 and hollow rivet 10, as heretofore, the hollow rivet 70 being spread inside of the head and its flange 11 holding the cloth, leather, or other material 12 between it and the flange 13 of the head. It is understood, of course, that the material 14 to which the female section is secured is 75 held between the cap 4 and the flange 5, as shown in Fig. 2, and that cap 4 is made up of two parts, as shown in the drawings.

With this construction, as is customary in this type of button, to button or fasten the parts it is simply necessary to force or snap the male section into the socket, when the parts will be held together, and to unfasten the parts the reverse action takes place.

A button thus constructed is strong and durable, is easy and simple to construct, and can be placed on the market at a comparatively small initial cost. At the same time it is easy to operate and efficient in the performance of its functions.

Slight changes might be resorted to in the form and arrangement of the several parts described without departing from the spirit and scope of my invention, and hence I do not wish to limit myself to the exact construction 95 herein set forth; but,

Having fully described my invention, what I claim as new, and desire to secure by Letters Patent, is—

As an article of manufacture, the combination of a button comprising a cap having an orifice in its lower side, and a knurled socket-section, the shank of which is thickened at its extreme end and inserted into the orifice in the cap and upset therein, the lower open end of said socket-section being split to give it resiliency, the interior being enlarged to a greater diameter than the outer end to form

an enlarged socket, the lower end of the socket portion being split and bent outwardly forming a circumferential flange, the outer edge being offset forming two planes one higher than the other, a ring fitted around the outer edge of the flange beneath the offset portion and spun around and over the upper surface of the offset portion, the internal diameter of the ring being of slightly greater diameter than the flange to permit of

the expansion of the flange within the ring, substantially as described and for the purpose as set forth.

In testimony whereof I affix my signature in presence of two subscribing witnesses.

HERMAN KERNGOOD.
